ELECTRIC TIME SWITCH

Filed June 24, 1926

— Inventor

LAWRENCE E. CHANCE,

By Oscar A. Michal

Attorney

UNITED STATES PATENT OFFICE.

LAWRENCE E. CHANCE, OF ST. LOUIS, MISSOURI, ASSIGNOR OF ONE-HALF TO ALEXANDER MILTENBERGER, OF ST. LOUIS, MISSOURI.

ELECTRIC TIME SWITCH.

Application filed June 24, 1926. Serial No. 118,271.

My invention relates to improvements in time switches and the primary object is the arrangement of a switch such that no motor or clock mechanism is required in the operation.

Another object is to so equip any ordinary incandescent lamp socket with my device so that a lamp in said socket will be extinguished after any predetermined duration of time 10 for which the operator has set it.

Another object is to provide a time switch which will positively require no motor in the operation thereof, breaking the current which controls it by the mechanism within the same.

A still further object is to provide a dual purpose switch as aforesaid that is economical in operation and comparatively simple to manipulate and very inexpensive to manufacture.

My improvement consists in the novel construction, arrangement and combination of parts as hereinafter fully, clearly and concisely described, definitely pointed out in my claims, and illustrated by the accompanying sheet of drawings, in which:

Figure 1 is a vertical enlarged sectional view of an ordinary lamp socket embodying my time switch principle therein;

Figure 2 is a fragmentary side view of the contactor and contact elements;

Figure 3 is a fragmentary side view of a modified form of contactor and contact elements;

Figure 4 shows the modified form of switch shown in Figure 2 in open position.

Referring now more specifically to the drawings, 7 indicates the outer brass casing being of the ordinary well known construction, at the lower opening of said casing is mounted the socket 8 by means of which the current is delivered to the lamp 9, a portion of which is shown in the drawing.

At the top of the lamp and in contactual relationship is the usual spring contact 10.

To hold up the contactor and contact elements and various binding posts, etc., in co-relationship I equip the ordinary lamp socket with a special porcelain fitting 11 which is adapted to hold all of the parts in as compact relationship as possible.

At one extremity of fitting 11 is an upright standard 12 upon which is carried for support bimetallic contactor element 13, this element 13 has wound upon its outer surface

At the free end of the contactor 13 is mounted an adjusting screw 15 which is composed of platinum or other suitable contact material.

To give the contactor 13 greater flexibility and to cause same to retract quicker I connect a helical tension spring 42 between the under surface of contactor 13 and the fitting 11 by an insulating connection.

By means of this screw 15 the gap F and the hinged contact element 16 may be varied so as to regulate the time the current is used and automatically extinguish the light at the predetermined time.

The contact element 16 is hingedly mounted at 17 the base of which is held in fixed relation by screw 18.

The contact element 16 is provided with another hinge at 41 and the uppermost part of this hinge has co-acting with the surface thereof a flat leaf spring 40 to give this uppermost hinged part a snap action and also to prevent this uppermost portion from snapping too quickly when pressure is brought to bear on the ball chain. The upper hinged part of the element 16 is so constructed that it cannot swing to a position any further to the right than shown in Figure 3.

A helical tension spring 19 is fastened at one extremity to fitting 11 and at the other extremity at an intermediate position to contact element 16. This spring tends to hold the element 16 in the inoperative position. Thus it will be seen that when it is desired to operate the switch the spring 19 having already retracted the contact 16 to the inoperative position it will now be necessary to pull the ball chain 20 which is trained through the bell shaped opening 21 in casing 7 and is also fastened at an intermediate point of contact 16. This will bring the contact 16 in the position as shown in Figure 1 and thereby cause all corresponding circuits to be completed and the lamp will be in operation.

In the meantime current is flowing through the high resistance coils 14 surrounding contactor 13 and the heat generated thereby will cause the body of the contactor to expand causing the end of same to withdraw forming a gap F between the platinum screw 15 and contact 16, and it will be readily seen that the time required before making the gap will depend upon the adjustment of the screw 15. After the gap is formed this will allow

the tension spring 19 to retract the contact 16 to the inoperative position ready to be set again by pulling ball chain 20.

5 The wiring of the switch may be traced as follows:—

10 The positive lead enters the top of socket and is trained through porcelain block 22 which is supported on brackets 23 and is then fastened to binding post 24. From thence two wires lead, one to the high resistance coils 14 and the other to the contact 10 above the lamp 9.

15 The negative lead likewise enters through top of socket and is trained through block 22 and then runs to binding post 18 supplying the current to the contact 16. Another wire connects the contactor extremity at binding post 25 to the socket base at binding post 26.

20 20 What I claim as new:—

1. In a time switch, an electrical resistance heat actuated contactor comprising many turns of high resistance wire, a body for said contactor composed of a flexible metallic 25 material having a tension spring to aid this flexibility, an adjustable screw provided at one extremity thereof, said contactor co-acting with a chain operated hinged contact element being provided with an extra spring 30 controlled hinge to give it a snap action.

2. In a time switch of the character described, an electrical resistance heat actuated contactor including a metallic body and a resistance wire carried thereby, and an adjustable member passed through one end of the 35 body and forming a contact, the adjustable member being adapted to coact with a manually operable spring tensioned break-jointed hinged contact provided with tensioning means to effect a snap action.

3. In a time switch of the character described, the combination with a heat actuated electrical contactor having an adjustable terminal, of a manually operable spring tensioned break-jointed hinged contact adapted 45 to coact with the first named contactor, and provided with tensioning means to effect a quick snap action.

4. The combination of a pair of contactors coacting with each other, of a time switch, 50 one contactor being thermostatically controlled and having an adjustable terminal contact, and the other contactor having a spring tensioned break-jointed arm and being hinged and manually controlled for actuation in one direction, and spring controlled for snap action in the opposite direction.

In testimony whereof I hereunto affix my signature.

LAWRENCE E. CHANCE
